UNITED STATES PATENT OFFICE

130,791

DESIGN FOR A NIPPLE

Cyril R. Porthouse, Kent, and William B. McIntosh, Akron, Ohio, assignors to The Pyramid Rubber Company, Ravenna, Ohio, a corporation of Ohio

Original design application November 16, 1940, Serial No. 96,634, now Design Patent No. 128,501, dated July 29, 1941. Divided and this application July 25, 1941, Serial No. 102,480

Term of patent 14 years

To all whom it may concern:

Be it known that we, Cyril R. Porthouse and William B. McIntosh, citizens of the United States, residing in Kent, county of Portage, and State of Ohio, and Akron, county of Summit, and State of Ohio, respectively, have invented a new, original, and ornamental Design for a Nipple, of which the following is a specification, reference being had to the accompanying drawing, forming part thereof, in which:

Figure 1 is a side elevational view of a nipple, showing our new design;

Figure 2 is a side elevational view of the nipple, looking at right angles to Figure 1; and

Figure 3 is a bottom plan view of the nipple.

This application is a division of our original application Serial Number D-96,634, filed November 16, 1940, now Design Patent No. 128,501, July 29, 1941.

We claim:

The ornamental design for a nipple, as shown and described.

CYRIL R. PORTHOUSE.
